DRIVE FOR WASHING MACHINE TUBS AND AGITATORS

George P. Castner, Webster City, Iowa, assignor to Solar Corporation, Milwaukee, Wis., a corporation of Delaware

Original application April 12, 1947, Serial No. 741,083, now Patent No. 2,648,213, dated August 11, 1953. Divided and this application July 31, 1952, Serial No. 301,876

5 Claims. (Cl. 74—70)

This invention relates to improvements in drive mechanisms for clothes washing machines and is a division from my copending application Serial No. 741,083 filed April 12, 1947, and now Patent No. 2,648,213, issued August 11, 1953. Also disclosed herein is a clothes washing machine similar in many respects to that shown in Patent No. 2,513,844, in which I am a co-inventor, and to a drive mechanism similar in some respects to that shown in Patent No. 2,513,845, in which I am sole inventor.

The invention further and more particularly relates to so-called automatic washing machines in which the clothes and cleansing liquid are agitated for washing purposes in an imperforate tub and in which the tub, following the washing action, is rotated at high speed for centrifugally expelling the cleansing liquid from the clothes. The various washing, rinsing and extraction cycles are carried out automatically in proper sequence and for proper periods of time. In the machine as shown in the prior application and patents and as disclosed herein, the washing action is carried out by the time proven agitator which is oscillated in and with respect to the tub itself and it is, therefore, necessary in order to operate this agitator, as well as to spin the tub for extracting the liquids, that suitable means be provided for transmitting oscillating motion to the agitator and rotary motion to the tub for controlled periods of time. As is well known to those skilled in the art all such machines have in common the problem of preventing excessive vibration when the tub is rotated for extracting the liquid, which vibrations are induced by the tendency of the tub to gyrate or precess as it is set in motion and brought up to centrifuging speed. Such gyration occurs as a result of the unbalanced load conditions in the tub, as represented by the wet clothes which are seldom if ever evenly distributed as to weight about the axis of rotation when the extraction begins. One satisfactory solution of this problem is disclosed in the two patents identified above, Patent No. 2,513,844 showing means for snubbing or frictionally and yieldably resisting the gyroscopic tendencies of the tub, whereas Patent No. 2,513,845 discloses a fluid drive or fluid coupling the operation of which permits a gradual acceleration of the tub as it is brought up to centrifuge speed. Such gradual acceleration of the tub is extremely important and is accomplished by using a fluid coupling having a high initial slippage factor, as set forth in the patent in question.

In the interest of economy and simplicity it is desirable to use a single prime mover, usually taking the form of an electric motor, for driving both the agitator and tub and it is the primary object of this invention to provide drive mechanism using a single motor, as contrasted with the two motors used in the prior patents, with means for transmitting torque from the motor through the fluid coupling to the tub itself and means for converting rotary to oscillating motion connected between the same motor and the agitator. It is further desirable in such machines for the motor to run continuously, but in order to take advantage of the high initial slippage characteristic of the fluid coupler this coupling must remain at rest, or idle, except when the tub is being rotated for extraction. It is a further object of my invention, therefore, to provide a drive mechanism, including a clutch for selectively transmitting

torque from the motor to the fluid coupling so that the coupling may remain at rest when not actually in use, and a second clutch for disabling the torque transmission from the motor to the agitator during the extraction process. According to my invention, therefore, the drive mechanism constituting the basis of this application comprises a single motor, a transmission device for converting rotating motion to oscillating motion and a clutch by which the latter motion may be selectively transmitted to the agitator, along with a fluid coupling with a high initial slippage characteristic connected to the tub and with another clutch for selectively driving the coupling from the motor.

These and other more detailed and specific objects 15 will be disclosed in the course of the following specification, reference being had to the accompanying drawings, in which:

Fig. 1 is a vertical sectional view, partially in elevation, and showing an automatic washing machine according to my prior disclosures but with the drive mechanism constituting the present invention.

Fig. 2 is an enlarged vertical sectional view of the fluid coupling and adjacent parts of the drive mechanism, as appearing to the lower left in Fig. 1.

Fig. 3 is a plan view of the drive mechanism showing all of the belting between the various parts thereof and showing certain supporting posts, as well as the agitator and tub connections in horizontal section.

Referring now more particularly and by reference 30 characters to the drawing, the construction of the washing machine itself will first be described in sufficient detail to enable an understanding of the present invention. The machine comprises an outer casing, or housing, designated generally at 10, which is divided into upper and lower chambers 11 and 12 by a horizontal partition plate 13, and which casing is provided at its upper end with a removable cover 14. At the lower end the casing 10 is supported by feet 15 upon the floor or other surface 16 and said lower end is provided with 35 a center bearing support 17 about which the inner assembly of the machine may gyrate. Said inner assembly constitutes essentially of a rotatable tub 18, into the open upper end of which the clothes and washing liquid may be placed, and this tub has a center mounting portion 19 by which it is fastened upon a tubular spindle 20 which is journaled in a bearing sleeve 21. The spindle 20 and sleeve 21 are disposed on an upright axis and extend downward through a tubular neck 22 forming part of the aforesaid partition plate 13. Below the plate 19 is connected to an upper frame plate 23 located in the lower chamber 12 and rigidly mounted by a series of spacer posts 24 to a lower frame plate 25, which in turn is supported by a U-shaped member 26 upon the aforesaid bearing 17 in a manner described in detail in the prior Patent No. 2,513,844. The collar 22 provides clearance for gyration of this entire assembly about the bearing 17 but such motion is resisted by snubbing mechanism, as set forth in that patent, and including a series of radially arranged springs 27 which are here shown and which extend between studs 28 upon the plate 23 and suitable brackets 29 secured to the inside of the casing 10. The spindle 20 extends downwardly below the upper plate and secured to the lower end of the spindle is a large belt pulley 30. It is not believed that a further detailed description of this tub arrangement and mounting is necessary herein in view of the prior disclosure, but it will be noted that the tub has upwardly flaring walls so that upon rotation of the tub the liquid content thereof will be centrifugally expelled in an outward and upward direction. Such expelled liquid may then pass off through a drain 31 in the partition plate 13 and the liquid is withdrawn by means of a pump 32 supported below the lower frame plate 25 with suitable connections to the drain 31, as clearly shown and also as set forth in the prior patent.

Also forming part of the machine is an agitator, designated generally at 33, located within the tub 18 and supported by means of a vertical shaft 34 extending down through the tubular spindle 20 to a point below the pulley 30, at which point the shaft is provided with one section 35 of a clutch. The other section 36 of such clutch is

secured to the output shaft of a transmission device 37 such as set forth in the prior patents and which is of the type converting rotary to oscillating motion. This transmission is secured to the underside of the lower frame plate 25 and has an upwardly extending input shaft, designated at 38, upon which is mounted a pulley 39 appearing in Fig. 3 herein. It will be clearly apparent that upon engagement of the clutch sections 35-36 the oscillating motion out of the transmission device 37 will be transmitted to the agitator shaft 34 to the agitator 33 to cause oscillation thereof about an upright axis and agitation of the contents of the tub by the vanes 40.

The transmission 37 is driven by an electric motor or other suitable prime mover, designated at 41, which is suspended below the lower frame plate 25 with its shaft extending upwardly therethrough. Mounted, then, upon this shaft 42 of the motor is a belt pulley 43 in horizontal alignment with the aforesaid pulley 39 and trained around these pulleys is a belt 44 connecting the motor to the input of the transmission. The aforesaid pump 32 also has an upwardly projecting shaft on which is mounted a belt pulley 45 and a belt 46 is trained around this pulley and a similar pulley upon the motor shaft 42 for driving the pump.

The tub 18 is rotated through the instrumentality of a fluid drive or fluid coupling, designated generally at 48, and for the construction of which attention is now invited particularly to Fig. 2. This coupling is substantially identical to that shown in my prior Patent No. 2,513,845 and comprises vaned driving and driven elements 49 and 50 having radial vanes 49^a-50^a in facing relation and superimposed one over the other. This coupling 48 is mounted upon an upright countershaft 51 which is supported in a bearing 52 and overhanging bracket 53 upon the lower frame plate 25 at one side of the machine. Upon this countershaft there is loosely mounted pulley 54 above the bracket 53 and this pulley is connected by a belt 55 to a pulley 56 at the upper end of the motor shaft 42. The pulley 54 is selectively connectable to drive the countershaft 51 through a clutch having an upper section 57, which is secured at 58 to a sleeve 59 journaled upon the countershaft and extending upward through the hub of the pulley and secured thereto by means of a set screw 60 or equivalent. The clutch further includes a lower section 61 secured to the countershaft 51 and axially slidably upward and downward thereon to control torque transmission between the pulley 54 and the shaft. This clutch section 61 is moved upward and downward by means of a bell crank shifter fork 62 fulcrumed at 63 upon the lower frame plate 25 and oscillated by means of a solenoid 64 in a manner which will be clearly apparent.

The driving element or impeller 49 of the fluid coupling 48 is centrally formed with a depending mounting sleeve 65 which is threaded at 66 upon the upper end of the countershaft 51 and locked thereto by means of a key 67. The driven element 50 of the fluid coupling is located below the driving element 49 and is centrally formed with an upwardly extending sleeve 68 journaled by means of bushings 69 upon the aforesaid sleeve 66 for free rotation with respect thereto. The driven element 50 of the coupling also constitutes the lower portion of an enclosing housing in conjunction with an upper housing section 72 overlying the driving element 49 and marginally secured by means of a peripheral weld 73, or equivalent, to the upper, outer edge of element 50. This housing construction thus forms a sealed chamber about the driving and driven elements of the coupling and said chamber is partially filled with a fluid, such as oil, to an amount substantially less than the total capacity of the chamber, as indicated in the drawing. For so filling the coupling a center plug 74 is removably threaded into the upper housing section 72 and it will be noted that there is provided a ball 75 and spring 76 for taking up any end play which may develop between the coupling parts, as set forth in detail in the parent application.

The driven element 50 of the fluid coupling is provided at its underside with a pulley 77, around which is trained a belt 78, through which torque may be transmitted from the fluid coupling to the aforesaid pulley 30 on the lower end of the spindle 20 which drives the tub 18.

As described above the fluid chamber of the coupling 48 contains less than the full capacity of the chamber and ideally is filled with fluid only to a point at which the vanes 49^a of the upper or driving element will clear the

fluid when it is at rest. In order to transmit torque through the coupling I then provide splash or dip vanes 79 which are secured to the driving element 49, inwardly of the radial vanes thereof, and which dip into the body of fluid at their lower ends. It will thus be understood that when the driving element 49 is set in motion these vanes 79 will gradually vortex the fluid so that it will rise into torque transmitting engagement with the vanes 49^a-50^a of both driving and driven elements, and as a result the coupling will have a high initial slippage factor.

In operation the agitator 33 is oscillated for washing the clothes by the motor 41 through the belt 44 operating over the pulleys 43-39 and driving the transmission 37, the oscillating output of which is connected through the clutch sections 35-36 to the agitator shaft 34. The clutch sections 35-36 are engaged during such operation by means of a solenoid and shifter fork, similar to that appearing at 62-64 herein and is described in detail in the prior disclosures. When the washing operation is completed the clutch sections 35-36 are disengaged in order to stop the agitator without stopping the motor 41 and the clutch sections 57-61 are now engaged so that the motor will be connected through the belt 55 and pulleys 54 and 56 to the countershaft 51. As this countershaft begins to rotate the driving element 49 of the fluid coupling is set in motion and the vanes 79 gradually bring the fluid in the coupling into driving engagement with the vanes 49^a-50^a on the driving and driven elements, whereupon the resulting rotation of the pulleys 77 will be transmitted through the belt 78 to the pulley 30 which drives the tub 18 through the spindle 20. The tub will thus be gradually accelerated, due to the inherent initial high slippage in the fluid coupling and the amount of such slippage will be determined to a large extent by the magnitude of the unbalanced load as represented by the wet clothes, as they rest unevenly about the axis of the tub following the washing operation. It will, of course, be understood that as the tub speed increases and the liquid is gradually centrifuged out of the tub the magnitude of this unbalanced load condition will decrease and the tub speed will continue to build up, so that the final extraction speed will be high enough for complete extraction but without at any time developing a gyrating or precessing action of an undesirable magnitude. When the centrifuging action is completed the clutch sections 57-61 may be disengaged and the tub 18 will stop ready for the next cycle of operation.

I have therefore provided a simple and effective drive mechanism permitting the oscillation of the agitator and rotation of the tub by means of a single motor and with provision for selectively connecting the fluid drive coupling to the motor, as is necessary in order to take advantage of the high initial slippage of the coupling for gradually accelerating the tub. In order to utilize this initial slippage factor of the coupling it is necessary that it operate only when the tub is to be rotated for centrifuging its liquid content, and to run the coupling continuously would be impractical from this standpoint.

It is understood that suitable modifications may be made in the structure as disclosed, provided such modifications come within the spirit and scope of the appended claims. Having now therefore fully illustrated and described my invention, what I claim to be new and desire to protect by Letters Patent is:

1. For a washing machine having a rotary clothes receptacle and an agitator oscillatable with respect to said receptacle, drive mechanism for the receptacle and agitator comprising in combination, a transmission for converting rotary to oscillating motion, a motor, a fluid coupling having cooperating vaned driving and driven elements arranged on an upright axis and means forming a sealed chamber about said elements and containing fluid for coaction with said vaned elements, means connecting the driven element of the fluid coupling to the receptacle, means including a clutch for selectively connecting the driving element of the coupling to the motor, and means connecting the motor through the transmission to the agitator and including a second clutch.
2. For use in a washing machine, a first member to be rotated, a second member to be oscillated with respect to the first member and a transmission drive of the type converting rotary to oscillating motion connected to the second member, a fluid coupling having cooperating vaned driving and driven elements and means forming a

sealed chamber thereabout containing fluid in an amount less than the total capacity of the chamber whereby a high initial slippage will occur with the transmission of torque through the coupling, means connecting the driven element of the fluid coupling to the first member, a single electric motor adapted to run continuously when the washing machine is in use, means including a first clutch for selectively driving the driving element of the coupling from the motor, and means including a second clutch for driving the second member from the motor through the said transmission device.

3. For use in a washing machine, a first member to be rotated, a second member to be oscillated with respect to the first, a fluid coupling having cooperating vaned driving and driven elements and means forming a sealed chamber about said elements and said chamber containing fluid for coaction with the said vaned elements, a countershaft and means supporting the fluid coupling on the countershaft and connecting the driving element and shaft, means connecting the driven element of the fluid coupling to the said first member, a single electric motor, means including a first clutch connecting the motor and countershaft for driving said driving element of the fluid coupling, a transmission device of the type connecting rotary to oscillating motion, and means including a second clutch for connecting the motor through said transmission device to the said second member.

4. For a clothes washing machine having a rotary clothes receptacle adapted to be rotated for centrifugally extracting cleansing liquid from the clothes and having as oscillating agitator for washing the clothes, drive mechanism comprising a single electric motor, a transmission for converting rotary to oscillating motion, means connecting the motor to drive the transmission whenever the motor is in operation, means including a clutch for selectively transmitting oscillating motion from the transmission to the agitator, a fluid coupling having upper and lower vaned elements and a housing forming a chamber about said elements for containing fluid to transmit torque from one vaned element to the other, means connecting

one of the vaned elements to rotate the clothes receptacle, and means for transmitting torque from the motor to the other of said vaned elements and including a clutch which when disengaged will cause the vaned elements to remain at rest while the motor is in operation.

5. For a clothes washing machine of the character described having a rotary clothes receptacle and an oscillatable agitator, a drive mechanism comprising in combination, a single electric motor having a shaft, a transmission for converting rotary motion to oscillating motion, a belt drive from the motor shaft to the transmission for transmitting torque, a shaft connected to the agitator, a clutch having cooperating clutch parts on the transmission and shaft for selectively transmitting oscillating motion to the agitator from the transmission, a fluid coupling having superimposed vaned driving and driven elements and a housing forming a sealed chamber about said elements containing fluid in an amount less than the total capacity of the chamber whereby there will be a high initial slippage through the coupling when the same is set in rotation from the stationary condition, a tubular shaft connected to the receptacle and surrounding the shaft connected to the agitator, a belt drive connecting the driven element of the fluid coupling to the tubular shaft, and another clutch connected between the motor shaft and the driving element of the coupling and engageable to transmit torque from the motor and set the coupling in motion from a stationary condition to transmit torque in turn to the receptacle with a high initial slippage.
